UNITED STATES PATENT OFFICE

2,523,450

TOOLHOLDER FOR CIRCULAR THREAD
FORMING TOOLS

René Rossetti, Geneva, Switzerland

Application December 26, 1945, Serial No. 637,271
In Switzerland December 27, 1944

3 Claims. (Cl. 10—104)

1

It is well known that in order to cut a screw thread with a forming tool on a lathe, it is necessary to set the cutting face of the tool at a predetermined angle with respect to a plane perpendicular to the axis of the screw. This angle is determined by the slope of the thread with respect to said plane, i. e. by the diameter and the pitch of the middle helix of the thread to be produced. According to actual practice, it is necessary to go through a trying process, to find the most favourable angle to be given to the tool and it is evident that the setting up is long and tedious and causes a great loss of time.

The invention has for its object a tool-holder tending to avoid these inconveniences due to the fact that it is equipped with a device for adjusting the angle of tilt of the tool with respect to a plane perpendicular to the axis of the thread to be formed. This device carries indicating means consisting of an index and a graduated scale capable of displacements one with respect to the other. Displacement transmitting members are provided between said indicating means and said tool causing a wide spread of the graduations as compared with the angular displacements performed by the tool during its adjustment. Clamping means are provided permitting the tool to be securely fastened in said tool-holder in the adjusted position.

Another object of the invention is a tool-holder in which the displacement transmitting members consist in a finger slidable in a slot provided in a stationary part and a groove cut in a part moving with the tool, said slot and groove forming a small angle.

A further object of the invention is a tool-holder in which the angle of tilt is obtained by means of a set of four wedge shaped rings, two of which being made to rotate simultaneously with respect to the two others.

Furthermore, another object of the invention is a tool-holder in which the tool is mounted on a rocking head provided with a ball rocking on a ball seat and around a stationary axle. A finger in the rocking head and a spiral shaped groove provided in the ball seat cooperating together constitute the displacement transmitting members.

The annexed drawings show diagrammatically and by way of examples, three forms of embodiment of tool-holders according to the invention.

Fig. 1 is a side view of a first form of embodiment.

Fig. 2 is an end view with a section along line II—II of Fig. 1.

2

Fig. 3 is a top view with a section along line III—III of Fig. 1.

Fig. 4 shows a second form of embodiment.

Fig. 5 is another view of the second form of embodiment with partial section represented at a larger scale.

Fig. 6 is a partial view of a third form of embodiment.

Fig. 7 shows a section along line VII—VII of Fig. 6.

Fig. 8 shows a detail of construction.

Fig. 9 is an end view.

The tool-holder represented in Figs. 1 to 3 is adapted particularly to the cutting of external threads. A circular forming tool 1 of a known type is secured on a holder 2. In view of obtaining a rigid connection between tool and holder, the former is mounted on an axle 3 with a conical head 4, a trued face of the tool bearing against a trued face provided on the holder. Axle 3 traverses said holder. A conical hole 5 is equipped with a split conical sleeve 6 slipped over axle 3, these parts being held firmly by a nut 8. The slopes of these cones being inverted, the clamping of the tool automatically causes its centering.

Holder 2 has a stem made up of a conical portion 9 and a longer cylindrical portion 7. Said stem is held in a clamping sleeve 10 with a square outer cross section or of other polygonal shape.

Sleeve 10 is bored out axially from end to end with a conical seat 11 to match said conical portion 9 of said stem. The latter is further equipped on its free end emerging from sleeve 10 with a screw thread 13 to cooperate with a clamping nut 12. Sleeve 10 has a longitudinal slot 14 parallel to axis 15. This slot is traversed by a finger 16 engaging with a groove 17 made in stem 7. This groove forming a small angle with axis 15, may be straight or a portion of a steep helix.

Finger 16 is provided with a shoulder 19 sliding in a groove cut in the edge of slot 14 and with a square portion preventing rotation of said finger around its axis. On said square portion is mounted an index plate 20 running over a graduated scale 21 located on one side of slot 14.

Lastly, the outer end of finger 16 is provided with a clamping nut 22.

The device just described may be used as follows:

Said sleeve 10 being meant to be clamped on the tool-carriage of the lathe (not shown) perpendicularly to the axis of the latter, it is sufficient to know the angle of incline of the middle helix of the thread with respect to a plane per-

pendicular to the axis of said helix. The forming tool is set by simply sliding said index 20 up to the desired division of scale 21, graduated in degrees, corresponding to said angle. Tightening of the nuts 22 and 12 clamps the tool in its correct position in the tool-holder. The latter may be clamped then as a whole by any known means on the tool-carriage in the manner prescribed above to have the forming tool correctly positioned and fastened.

From the above, it may be observed that the angular setting of the tool in the tool-holder is an extremely easy and quick operation. It requires no fumbling, no trying, thereby allowing an important time saving.

As shown on the drawing, scale 21 may be preferably divided down to fractions of degrees and slot 17 is arranged so as to permit the tool to be inclined in one direction or the other with respect to the plane perpendicular to the axis of the screw depending on whether a right hand or a left hand thread is to be cut.

The form of embodiment represented by Figs. 4 and 5 pertains particularly to the cutting of internal threads.

The tool-holder comprises a stem 25 of circular cross section sliding in a clamping sleeve 26, with a longitudinal split affording a slight elasticity. This stem is provided with two diametrically opposite longitudinal grooves 31a and 31b, one of them serving as a guide for a finger 27 secured to clamping sleeve 26.

One end of stem 25 is turned down to a smaller diameter, so as to form an arbor 43. A shoulder 29 thus formed takes up the thrust exerted by a bolt 37 screwed on the end of arbor 43, clamping a forming tool 1 by its shoulder 40 and by the intermediary of four wedge shaped rings 30, 35, 38 and 39 of equal taper, one face of each ring being square with its axis, the other face being oblique. The extreme rings 30 and 38 are held angularly with respect to 43, i. e. with respect to stem 25 by keys 32 and 32a respectively. They have their square face, with respect to the axis 34 of stem 25, directed against shoulder face 29 and bolt 37 respectively, their slanting face being parallel to each other. The middle rings 35 and 39 have their oblique face 36 and 39a applied on oblique faces 33 and 38a of rings 30 and 38 respectively. A finger 44, secured in ring 35 and engaging with a radial groove 47 provided in ring 39, keeps these rings in a constant angular position one with respect to the other, their oblique face being parallel to each other, regardless of the angular displacement which may be imparted to ring 35 provided with radial sockets 57. Forming tool 1 has a sleeve 41 equipped with an internal shoulder serving for the clamping of the tool between said middle rings 35 and 39. Inner surfaces 45 and 46 of said inner rings 35 and 39 are rounded off so as to provide for the necessary clearance space for arbor 43.

It may be seen readily that, owing to this arrangement, the end faces of the ring pile always remain square with respect to the stem axis and that the total distance between faces 36 and 39a remains constant, regardless of the angular position given to adjusting ring 35, and that the axis of forming tool 1 may be brought to form an angle of tilt with the axis of stem 25 varying between 0 and twice the angle of taper common to all four wedge shaped rings.

This device functions as follows:

The proper inclination of the forming tool with respect to axis 34, given by the diameter and

pitch of the thread to be cut, is set by turning adjusting ring 35 by means of a rod or a key (not shown) engaging with sockets 57. When an index 48 provided on ring 35 (Fig. 4) matches with 5 a division of a graduated scale 49 provided on ring 30 and corresponding to the prescribed angle, end bolt 37 is tightened. The tool-holder may then be clamped as a whole by any known means, with its axis 34 parallel with the axis of the 10 thread to be cut, on the tool-carriage of the lathe not shown, split sleeve 26 affording very reliable clamping conditions.

Depending on whether a right handed or a left handed screw is to be obtained, finger 27 of sleeve 15 26 is engaged either with longitudinal groove 31a or 31b. It will be noted that due to the fact that the end faces of the ring pile remain parallel and perpendicular to axis 34, bolt 37 is subjected to traction alone.

20 This form of tool-holder for internal thread forming tools affords great advantages in that it permits the tool to be adjusted easily and rapidly in its angular position with respect to a plane perpendicular to the axis of the thread to be cut.

25 In the form of embodiment shown on Figs. 6 to 9 a forming tool 1 is secured to the end of a stem 25 of circular cross-section sliding in a longitudinally split clamping sleeve 26. Stem 25 is provided with two longitudinal and diametrically opposite grooves 31 (one of which alone being shown). With one of these grooves is engaged a finger 27 secured to clamping sleeve 26.

The end of stem 25, turned down to a smaller diameter, is equipped with an axle 51, with its 35 axis perpendicular to and crossing axis 50. On said axle 51 is mounted a tiltable head 52, carrying, rigidly clamped to its front face, a forming tool 1. The resting surface of said head 52 is a portion of a sphere engaging with a spherical seat 53 provided in a ring 54. Said ring rests on a shoulder of stem 25 and is provided with a spherical spiral shaped groove 55. The protruding end of a finger 56 fastened and guided in a recess in said head cooperates with said groove.

45 A cylindrical ring 57, bearing an index 58 facing a graduated scale engraved on the lower edge of said ring 54, is slipped over stem 25 and prevented from rotating around same by a key 60.

Lastly, a knurled nut 61 screwed on a thread 50 62 cut in stem 25 allows said head to be clamped in the desired position.

The described device functions as follows:

Nut 61 having been loosened it is sufficient to cause ring 54 to rotate on stem 25. During this 55 adjusting, spiral groove 55 guides finger 56 thereby causing head 52 to rock on its seat 53. The angle of tilt of head 52 varying in a continuous manner with the rotation of ring 54, it is possible to obtain a very precise angular setting of the 60 angle of tilt of the forming tool with respect to axis 50.

Tightening nut 61 towards the tool end of the tool-holder causes axle 51 to clamp head 52 on its seat 53.

65 It is evident that in order to obtain a good performance of the described device it is necessary that the spiral groove be of the proper shape. The middle line of each section through a plane containing the axis 50 must be tilted with respect 70 to said axis by an amount equal to the angle of tilt to be obtained for the head when finger 55 shall have its axis in said plane. In order to avoid inaccuracies of setting due to play between finger and guiding groove, it is of advantage to 75 provide the end of the finger with a short cone

as shown in Fig. 7 the shape of the guiding groove being then made to match.

It may be seen that in this latter form of construction the tool is made to rock around an axis whose position does not vary with respect to the stem of the tool-holder. This axis being perpendicular to that of the stem, it follows that the angle of inclination of the cutting edge of the forming tool does not vary during the setting of the aforesaid angle of tilt. This peculiarity has important advantages as it becomes unnecessary, as was the case with the device of Figs. 4 and 5, to verify the angular setting of the cutting edge for each modification of the angle of tilt of the tool, a tedious operation owing to the fact that during adjusting of the angle of tilt, the instantaneous axis of rotation varies and is difficult to locate.

It is evident that a tool-holder according to the invention may show different alternatives as to the details of construction as compared with the forms represented schematically and by way of examples on the annexed drawings. The essential feature is that said tool-holder is equipped with a device enabling the forming tool to be set and secured at the prescribed angle of tilt with respect to a plane perpendicular to the axis of the thread to be formed, with the assumption that said tool-holder is secured itself at a predetermined angle with respect to the axis of said thread.

The angle of tilt of the thread forming tool usually not exceeding a few degrees, it becomes possible, in order to allow for a precision setting, to provide the device with a widely spread graduation for the indication of said angle. In the forms of embodiment represented, the spreading of the scale has been made possible either by the use of a helical groove or inclined planes or a spherical spiral groove, but it is evident that any other known mechanically equivalent device may be used.

I claim:

1. A tool holder for a circular thread forming tool movable in a path parallel to the axis of the work piece to be threaded comprising an elongated substantially horizontal tool mount of polygonal cross section having a longitudinal bore, a rod axially slidably mounted therein, a shaft carried by one end of said rod perpendicular to the axis of said rod and substantially vertical, a head pivotally mounted on said shaft for rocking movement about the same, a circular thread forming tool carried by said head, a ring member rotatably mounted on said rod and provided with a spiral groove in the end face thereof adjacent said head, a finger carried by said head and extending into said groove whereby rotary movement of the groove carrying ring about the rod will effect rocking movement of the head and thread cutting tool about said shaft.

2. A tool holder for a circular thread forming tool movable in a path parallel to the axis of the work piece to be threaded comprising an elongated substantially horizontal tool mount of polygonal cross section having a longitudinal

bore, a rod axially slidably mounted therein, a shaft carried by one end of said rod perpendicular to the axis of said rod and substantially vertical, a head pivotally mounted on said shaft for rocking movement about the same, a circular thread forming tool carried by said head, a ring member rotatably mounted on said rod and provided with a spiral groove in the end face thereof adjacent said head, a finger carried by said head and extending into said groove whereby rotary movement of the groove carrying ring about the rod will effect rocking movement of the head and thread cutting tool about said shaft, said head having a rear portion of semi-spherical form and said ring having a semi-spherical socket formed in the grooved end face thereof to receive and cooperate with said head.

3. A tool holder for a circular thread forming tool movable in a path parallel to the axis of the work piece to be threaded comprising an elongated substantially horizontal tool mount of polygonal cross section having a longitudinal bore, a rod axially slidably mounted therein, a shaft carried by one end of said rod perpendicular to the axis of said rod and substantially vertical, a head pivotally mounted on said shaft for rocking movement about the same, a circular thread forming tool carried by said head, a ring member rotatably mounted on said rod and provided with a spiral groove in the end face thereof adjacent said head, a finger carried by said head and extending into said groove whereby rotary movement of the groove carrying ring about the rod will effect rocking movement of the head and thread cutting tool about said shaft, said head having a rear portion of semi-spherical form and said ring having a semi-spherical socket formed in the grooved end face thereof to receive and cooperate with said head, and a nut threaded on said rod and engaging the opposite end of said ring to press the latter against said head to retain the head in adjusted positions.

RENÉ ROSSETTI.
